JOHN NICHOLS, OF PATERSON, NEW JERSEY.

Letters Patent No. 83,723, dated November 3, 1868.

IMPROVEMENT IN MACHINE FOR BURRING WOOL.

The Schedule referred to in these Letters Patent and making part of the same.

To all whom it may concern:

Be it known that I, JOHN NICHOLS, of Paterson, in the county of Passaic, and State of New Jersey, have invented a new and useful Improvement in Burring-Machines; and I do hereby declare that the following is a full, clear, and exact description thereof, which will enable others skilled in the art to make and use the same, reference being had to the accompanying drawings, forming part of this specification, in which—

Figure 1 represents a vertical longitudinal section of my improved burring-machine, taken on the plane of the line $x\ x$, fig. 2.

Figure 2 is a vertical transverse section of the same, taken on the line $y\ y$, fig. 1.

Figure 3 is a detail side view of the toothed retaining-strip.

Figure 4 is a transverse section thereof.

Similar letters of reference indicate like parts.

The object of this invention is to construct a machine for burring wool, which will not tear nor injure the wool, and which will operate with great rapidity and effectiveness.

The invention consists in the combination of the drum, having a toothed triangular band wound around it, the notched blade for removing the burrs from the drum, the revolving brush, and the reel.

A, in the drawing, represents a wooden or other frame, of suitable size and shape, holding the journals of three horizontal transverse shafts, B, C, and D.

On the shaft B is mounted a drum, E, of suitable diameter and length.

This drum is provided with a toothed grooved surface, by having a narrow toothed metal band, F, wound spirally around it. This band is of triangular cross-section, as in fig. 4, and when it is wound around the drum, its various layers touch each other at their base, while they are clear from each other on their outer edges. A spiral groove is thus formed between the windings of the toothed spiral band, to receive the wool.

The roller C carries a reel or striking-bars, G, and on the roller D is mounted a cylindrical brush, H, as shown.

I is a blade set up in front of the drum E, quite close to the same, and between the drum and the reel G.

The upper edge of the blade I is fingered, or, rather, notched, and is very close to the toothed rim of the

drum. The object of having these notches is to prevent the burrs from being balanced on the edge of the blade I, and from being thereby squeezed down between the blade and the drum.

The brush is under the blade I, and is in contact with the rim of the drum. It is encased all around, excepting the space between the blade I and the drum, and excepting also a discharge-opening, a, for the wool.

The operation is as follows:

The drum, by means of its teeth, takes the wool from a suitable feeding-apparatus, and deposits it in narrow strips in its grooves, so as to protect the said wool from injury. The burrs, of course, project, and are, by the blade I, separated from the drum. All the rollers revolve in the directions indicated by the arrows in fig. 1. The burrs that have been taken off the drum by the blade are struck by the reel, and separated from the woolly fibres to which they may have adhered. They then fall upon a table, J, and are thence discharged into a suitable receptacle.

The wool is thus cleared from the burrs, and is then taken off the drum by the brush H, by which it is thrown through the discharge-opening a, of its case K, into a suitable receptacle.

The band F is to rest firmly on the surface of the drum, and is provided with a concave lower surface, as in fig. 4, so that it will not be able to swing on inequalities projecting from its middle.

The rollers receive their rotary motion from suitable mechanism.

The band F is arranged in close windings, and its ends are both fastened to the drum in suitable manner. The band F, instead of being wound spirally around the drum E, may be fitted around the same in rings, that form separate grooves between them.

Having thus described my invention,

I claim as new, and desire to secure by Letters Patent—

A burring-machine, consisting of the combination with each other of the drum E, having the toothed triangular band F, of the notched blade I, rotating reel G, and brush H, all made and operating substantially as herein shown and described.

JOHN NICHOLS.
